GUY M. RUSSELL, OF ROCHESTER, NEW YORK, ASSIGNOR TO AMERICAN PIANO COMPANY, OF NEW YORK, N. Y., A CORPORATION OF NEW JERSEY.

TREADLE-SHIFTING AND DOOR-OPERATING MECHANISM FOR AUTOMATIC PLAYER-PIANOS.

1,252,035.

Specification of Letters Patent.

Patented Jan. 1, 1918.

Application filed June 2, 1914. Serial No. 842,499.

To all whom it may concern:

Be it known that I, GUY M. RUSSELL, a citizen of the United States, and a resident of Rochester, county of Monroe, and State of New York, have invented an Improvement in Treadle-Shifting and Door-Operating Mechanism for Automatic Player-Pianos, of which the following description, in connection with the accompanying drawings, is a specification, like characters on the drawings representing like parts.

This invention relates to foot-power player-pianos and the like, and pertains more particularly to apparatus for moving the pumping treadles into and out of operative position, the mechanism for this purpose being combined, if desired, with means for opening and closing a door in the bottom of the instrument through which the treadles are moved into and out of operative position.

Among other objects, the invention is intended to provide a convenient means for governing the movement of the treadles and also, if desired, to provide co-operating means for moving the treadles and the door.

The invention may be readily understood by reference to one illustrative embodiment shown in the accompanying drawings, in which:

Figure 1 is a front elevation of playing treadles with a portion of the base of a player-piano or the like;

Fig. 2 is a detached detail of certain parts shown in Fig. 1;

Figs. 3 and 4 are detached details showing parts of the operating mechanism in different positions;

Figs. 5 and 6 are both sections of Fig. 1; and respective figures show different positions of the treadles.

The treadles 7, 7, are hinged to a treadle support 8 which may be provided with feet 9 preferably having rubber treads. The treadles are provided with pivoted thrust bars 10 by which they are connected with a pitman 11 for operating the pumps or feeder bellows which are unnecessary to be shown.

The treadle support 8 is secured to rocking arms 15, 15, fixed to, or conveniently made integral with, coaxial shafts 16, 16, journaled in any suitable manner inside the base of the player. The treadles are swung

into and out of operative position upon the shafts 16. The operative position, *i. e.* when the treadle is in position to be operated for pumping, is shown in Fig. 6 and the in-operative position, *i. e.* when the treadles are retracted into the base of the player, is shown in Fig. 5.

The bottom panel which incloses the base of the player, is shown at 18 and the key-bed for the player is shown at 19.

A door-way 20 in the panel 18 permits the treadles and connected parts to be swung from within the base of the player to the operative position and back again. It is preferred that when the treadles are in operative position the door-way in the panel 20 shall be closed, and for this purpose a door 22 is provided. The door 22 has eye-pieces 23, 23, slidably mounted upon a shaft 24 which is fixed in brackets 25, 25, secured to the panel 18—the door 22 sliding lengthwise the shaft 24 to close and open the door-way 20.

The illustrative embodiment of the invention comprises a single actuator, shown as a hand lever under the key-bed, for performing the two offices of moving the treadles into and out of operative position, and also opening and closing the door 22 at appropriate times. It is not indispensable that these two operations be controlled by a single means. The specific means for moving the treadles will be first described.

The treadles are moved from the position shown in Fig. 5 to that shown in Fig. 6, and vice versa, by rocking the shafts 16 and thereby rocking the arms 15.

For this purpose a crank arm 30 is fixed upon a shaft 16 and has pivoted to it a vertically movable rod 31 having its upper end mounted to slide vertically in the key-bed 19 or other convenient part. By moving the rod 31 vertically, the crank arm 30 is rocked and thereby the shaft 16 is rocked to move the treadles.

Fixed upon the rod 31 are two fingers 33, 34, by which the rod is vertically reciprocated. A lug 36 is adapted to be inserted between the fingers 33 and 34 at appropriate times in order to reciprocate the rod 31, this lug 36 being mounted upon a crank arm 37 which is fixed to a hand-operated shaft 38. As shown in Figs. 5 and 6, the shaft 38 is journaled in brackets fixed upon the bottom

of the key-bed and at a point within easy reach of an operator seated at the instrument the shaft 38 is provided with a handle 39 by which to rock the shaft.

5 When the parts are in the position shown in Fig. 1 the treadles 7, 7, are in the operative position shown in Fig. 6. If the handle 39 be rocked in a clockwise direction from the position shown in Fig. 1, the lug 36, acting upon the finger 34, will force the rod 31 downwardly and will thereby rock the crank arm 30 in a contraclockwise direction, as shown in Fig. 6, thereby moving the treadles from the position shown in Fig. 6 to that 10 shown in Fig. 5. The lug 36 remains in engagement with the finger 34 on the rod 31 long enough to enable the treadles to be retreated as far as necessary. Thereafter, if the handle 39 be rocked contraclockwise in 15 Fig. 1, the lug 36 will engage the finger 33 and force the rod 31 upwardly to rock the crank arm 30 in a clockwise direction from the position shown in Fig. 5, thereby to move the treadles from inoperative to operative 20 position.

To relieve the operator from the necessity to exert the full amount of force upon the handle 39, which may be necessary to move the treadles back and forth, an arrangement 25 of springs is shown in the accompanying drawings which materially assist the movement of the treadles. A spring 40 (Figs. 5 and 6) is secured at one end to a bracket 41 fixed upon the base of the player, and at its 30 other end to a crank arm 42 fixed upon the shaft 16. The spring 40 is so located and is of such length, that it exerts no material pull upon its arm 42 of the shaft 16, when the parts occupy the position shown in Fig. 5. 35 As the treadles are moved outwardly, however, (clockwise in Fig. 5) the spring 40 begins to be tensioned from the time its arm 42 is substantially horizontal, and is thereafter 40 increasingly tensioned until the arm 42 reaches the substantially vertical position 45 shown in Fig. 6. The spring 40 is preferably so adjusted that this increasing tension substantially balances the increasing effective weight of the treadles as they move outwardly from the position in which their center of gravity is substantially vertically 50 above the shaft 16 upon which they rotate. In other words, the weight of the treadles and their immediately connected parts, is 55 supported practically entirely by the increasing tension of the spring 40, during the time the treadles are moved toward the operative position, from the intermediate position in which their center of gravity is above the 60 shaft 16; therefore, the only force necessary to be exerted by the operator upon the handle 39 is that force which is necessary merely to overcome the balance between the spring 40 and the weight of the treadles and 65 other parts, and force the treadles into the

position shown in Fig. 6. Likewise, in moving the treadles from the position shown in Fig. 6 back into the base of the player (the spring 40 being then tensioned to balance the maximum effective weight of the treadles and other parts) it is only necessary for the operator to apply a slight force to the handle 39 and thereby assist the spring 40 to return the treadles toward inoperative position.

A second spring 50 (at the left in Fig. 1) 70 has its upper end secured to a stationary bracket 51 mounted on the frame of the player and its other end secured to a crank arm 52 fixed upon the shaft 16 and preferably alined with the crank arm 42 for the 75 spring 40. When the parts are in the position shown in Fig. 6 the arm 52 is substantially vertical and the spring 50 is so far relaxed as to exert no material pull upon the arm 52; and the spring 50 is preferably so 80 adjusted that it does not exert any substantial pull upon its arm 52, as the latter moves contraclockwise in Fig. 6, until the treadles have reached and passed the position in which their center of gravity stands above 85 the shaft 16. Thereafter, however, in moving the treadles toward the position shown in Fig. 5, the arm 52 increasingly tensions the spring 50 so that the increasing effective 90 weight of the treadles toward the end of its retreating movement, is substantially balanced by the spring 50. When the parts come to rest in the position of Fig. 5, the spring 50 is tensioned, preferably to an extent sufficient substantially to balance the 95 weight of the treadles 7 and other parts; and therefore the operator need exert only enough force upon the handle 39 to assist the spring 50 to move the treadles 7 and the other parts outwardly until the spring 40 begins to be tensioned, whereupon the handle 100 37 is moved, as already explained, with only enough force to assist gravity in moving the treadles, against the increasing tension of the spring 40 into the position shown in 105 Fig. 6.

Obviously, it is not essential that there be any precise balancing relations between the effective weights in different positions of the treadles 7, and the opposing tensions of the 110 springs 40 and 50. Various adjustments or arrangements of these springs or their equivalents would serve to assist in the movement of the treadles without necessarily producing any substantial balancing effect, although, as will be evident to those skilled in the art, an approximate balancing is desirable.

Besides assisting the operator in moving the treadles back and forth, the springs may 115 (and do in fact in the illustrative embodiment) desirably cushion and retard the movement of the treadles so as to avoid their dropping abruptly into one position or the other.

For the purposes of the specific arrangement shown in the drawings, it is desirable to utilize the same handle 39 for closing the door 22 after the treadles have been retreated into the position shown in Fig. 5. For this purpose the shaft 38 is provided with a crank arm 60 connected by a bent link 62 with a lever 63 fulcrumed at 64 to a bracket on the bottom of the key-bed. The lower end of the lever 63 is pivoted at 66 to a link 67 secured (at its left hand end in Fig. 1) to a bracket 68 fastened upon the inner face of the door 22. When the lever 63 is rocked to the left in Fig. 1, the door 22 slides to the left on its supporting shaft 44 and closes the door-way 20.

When the treadles 7 are in the operative position shown in Fig. 6, their pump-operating links 10 extend through the doorway 20; hence at such times the door is desired to remain open. Likewise the door is preferred to remain open until the treadles have been sufficiently retreated into the interior of the base to avoid interference with the closing door. This is provided for by the illustrative means for closing the door by the handle 39.

When the parts are in the position shown in Fig. 1, the door 22 stands wide open and the treadles stand in the operative position of Fig. 6. The handle 39 being then moved clockwise, the bar 31 is forced downwardly to rock the treadles toward inoperative position. This downward movement of the rod 31 begins immediately the handle 39 is moved clockwise, but the door closing crank arm 60 is so positioned on the shaft 38 that during the first part of the movement of the handle 39 and the retreating movement of the treadles, the lever 63 is not materially moved. When, however, the rod 31 has been moved downwardly far enough to substantially complete the retreating movement of the treadles, the lever 63 begins to move clockwise in Fig. 1 to start the closing of the door 22. During this treadle retreating and door closing movement, the door preferably has the latter part of its movement after the retreated treadles have substantially come to rest. Therefore, the parts are so arranged, as shown in Fig. 4, that, when the rod 31 has positively thrown the treadles beyond the position where their center of gravity stands above the shaft 60, the lug 36 on the treadle operating crank arm 37, passes out of engagement with the finger 31, whereupon the shaft 38 may be moved still farther to rock the parts to the position shown in Fig. 3, wherein the door 22 is completely closed to cover the treadles and restore the finished panel appearance of the base panel 18.

On the door-opening and treadle-advancing movement, the handle 39 is rocked counter-clockwise from the position shown in

Fig. 3 thereby starting to open the door and at least partially completing that opening, before the lug 36 engages the finger 33 to start the treadle-advancing movement. Thus the door is got out of the way to permit the treadles to be thrown out through the doorway 20 during the latter part of the contraclockwise movement of the handle 39.

As is well known to those skilled in the art, it is oftentimes desirable to remove the base panel 18 to permit inspection or repair of the apparatus in the base of the player. When the door 22 is mounted upon the panel 18, as in the illustrative instance of the drawings, it is desirable that this door be readily removable with the base panel 18. If, however, the door were more or less rigidly connected in any manner with the key-bed or other fixed part of the player, such connection would interfere with, or perhaps prevent, a ready removal of the base panel. To avoid any such difficulty, one aspect of the present invention comprises means for permitting the panel 18 to be moved out while maintaining the continuity of the door operating mechanism comprising the lever 63 which is secured to a bracket on the bottom of the key-bed. The link 27 consists of two parts connected by a turn-buckle 70. This turn-buckle permits the left-hand part (in Fig. 1) of the link 67 to be rotated relatively to the right-hand end of the link which is pivoted at 66 to the lever 63. Also, as shown in Figs. 2 and 5, the extreme left-hand end of the link 67 has a vertically disposed pin 72 which passes through an extension 73 upon the bracket 68 which is secured to the door 22. With the described arrangement, the panel 18 may be rocked clockwise in Fig. 5 upon fulcrums provided by the usual pins 75 and the base of the player may thus be open to inspection and repair, without disorganizing the train of door-closing mechanism between the handle 39 and the door 22.

This train of mechanism may, however, be sufficiently disorganized to permit entire withdrawal of the panel 18 and door 22 if it be desired to separate them from the instrument instead of merely swinging the panel outwardly on the fulcrum provided by the pin 75. For this purpose the left-hand end of the link 67 may be made detachable from the bracket 68. For example, the left-hand end of the link 67 comprises cooperating leaves 77, 78, one of them carrying the pin 72 which passes through the projection 73 on the bracket 68, and the other leaf 77 engages the pin 72 to hold it in engagement with the projection 73. Preferably, one or both of the leaves 77, 78, is or are a leaf spring or leaf springs, so as to insure a proper mutual engagement thereof with the pin 72. The leaves 77 and 78 may be secured to the remainder of the

link 67 in any practicable manner, as by having the leaf 78 extended to an elbow to be engaged by a reverse elbow of the link, as illustrated in Fig. 2.

5. It is to be understood that the invention is not limited to the precise construction, organization and mode of operation shown in the drawings and described above for illustration. On the contrary, the invention 10 may be variously embodied, and the illustrative construction may be variously modified within the proper scope of the subjoined claims. It is not indispensable that all the 15 features of the invention be used conjointly, since, in some instances, they may be used separately to advantage.

I claim as my invention:—

1. In a musical instrument, the combination 20 of a removable base panel having a door-way; a door connected to said panel and removable therewith; door operating means connected to another part of the instrument; and connections between said mechanism and the door permitting removal 25 of the base panel from its normal position while maintaining said connections.

2. In a musical instrument, the combination 30 of a removable base panel having a door-way; a door connected to said panel and removable therewith; door operating means connected to another part of the instrument; and detachable connections between said mechanism and the door.

3. In a musical instrument, the combination 35 of a removable base panel having a

door-way; a door connected to said panel and removable therewith; door operating means connected to another part of the instrument; and detachable, resiliently engaged connections between said mechanism 40 and said door.

4. In a player piano the combination of a rock shaft mounted within the base of the instrument, swinging treadles operatively connected therewith, a rock shaft mounted 45 upon the key bed, means operatively connecting said key bed rock shaft during substantially half its movement to the first rock shaft; a removable base panel, a door slidably mounted upon said base panel, and 50 means flexibly connecting said door and said key bed rock shaft to permit forward movement of the base panel without detaching said connecting means.

5. In a musical instrument the combination 55 of a removable base panel having a door-way, a door mounted upon said base panel and removable therewith, door operating means including a lever depending from the key bed of the instrument, and means connecting said door and said lever to permit limited forward movement of the base panel without disengaging said connections.

In testimony whereof, I have signed my name to this specification, in the presence of 60 two subscribing witnesses.

GUY M. RUSSELL.
